UNITED STATES PATENT OFFICE

2,553,862

CONVERTIBLE CRIB AND CRADLE

George Leslie Morris, Winchendon, Mass.

Application April 15, 1950, Serial No. 156,151

2 Claims. (Cl. 5—105)

1

This invention relates to a device or article of furniture which is readily convertible for use either as a crib or as a cradle. The change from crib to cradle or vice versa is accomplished by simple inversion of the article, which in one position rests on four spaced foot portions and in the inverted position rests on a pair of rockers.

It is one important object of the present invention to provide such a device with a mattress support which automatically assumes a different operative position whenever the article is inverted.

A further object is to provide a mattress frame so designed that assembly of a prefabricated mattress frame with prefabricated crib side members is facilitated.

My invention further relates to arrangements and combinations of parts which will be hereinafter described and more particularly pointed out in the appended claims.

A preferred form of the invention is shown in the drawings, in which

Fig. 1 is a perspective view of the device in "crib" position;

Fig. 2 is a similar view with the device in "cradle" position; and

Fig. 3 is a fragmentary sectional plan view, taken along the line 3—3 in Fig. 2.

Referring to the drawings, my improved convertible crib and cradle comprises end members 10 and 11 and crib side members S having upper side rails 12 and lower side rails 14. All of the side rails are permanently secured to the end members in any convenient manner, as by screws 16.

Each upper side rail 12 is connected to its associated lower side rail 14 by a plurality of upright slats 20, and each side member S comprising an upper rail 12, a lower rail 14 and a plurality of slats 20, is assembled and prefabricated as a unit before being secured between the end members 10 and 11.

The mattress frame F comprises end frame members 30 and 31 spaced apart by a plurality of longitudinal slats 32. The parts 30, 31 and 32 are also assembled and prefabricated as a unit before assembly in the crib or cradle.

Each end member 30 or 31 rests on the top surfaces of the lower side rails 14 when the device is positioned for use as a cradle, and similarly rests on the corresponding edges of the top rails 12 when the structure is inverted.

Each outer end portion of each end member 30 or 31 has a deep notch 35 (Fig. 3) to receive the outer edge 20a of one of the outside slats 20.

The edge 20a is nearer the inner surface of the end member 10 than the width of the member 30, and the distance between the outer edges 20a of the two outside slats 20 is greater than the distance between the facing edges of the end frame members 30 and 31.

2

The mattress frame F is thus securely held from accidental displacement but is at the same time freely movable vertically, so that it will drop automatically to a lower and different operative position whenever the article is inverted.

Each notch 35 is also made deep enough so that the prefabricated mattress frame F may be assembled with the prefabricated side members S before the side rails 12 and 14 are secured to the end members 10 and 11. It is thus possible to ship the article "knocked-down" and to easily and quickly assemble the article after shipment.

Obviously the article may be made in different sizes and may be used either as an article of children's furniture or as an article of doll's furniture.

Having thus described my invention and the advantages thereof, I do not wish to be limited to the details herein disclosed, otherwise than as set forth in the claims, but what I claim is:

1. In a convertible crib and cradle, separated end members each having one curved supporting surface and a reverse supporting surface with transversely spaced foot portions, side members each comprising upper and lower side rails connecting said end members, said side members having vertical side slats mounted between said upper and lower rails, a mattress frame supported on said side rails in either position of said end members, said frame being held from displacement by said side slats and being freely slidable vertically between the upper and lower side rails when the article of furniture is inverted, and spaced end frame members with the outer end portions thereof extending over the side rails on which said frame is supported and said outer end portions having deep notches on their facing edges to loosely receive the outside slats in said side rails after assembly of a prefabricated mattress frame with a pair of prefabricated side members.

2. The combination in a convertible crib and cradle as set forth in claim 1, in which the facing edges of the end members of the mattress frame are nearer together than the outer edges of the outside slats in said side members, and in which the bottoms of the notches in the end members of the mattress frame are spaced further apart than said outer edges of said outside slats.

GEORGE LESLIE MORRIS.
